UNITED STATES PATENT OFFICE.

FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

EXPRESSION-CONTROLLER.

1,093,228.

Specification of Letters Patent. Patented Apr. 14, 1914.

Application filed January 27, 1913. Serial No. 744,280.

To all whom it may concern:

Be it known that I, FRANK C. WHITE, a citizen of the United States, residing at Meriden, county of New Haven, Connecticut, have invented certain new and useful Improvements in Expression-Controllers, of which the following is a full, clear, and exact description.

My invention relates to an improvement 10 in music playing instruments and note sheets therefor, and consists in providing a new and useful means for automatically controlling the expression of the composition being rendered.

15 The character and importance of the improvements will be apparent when the construction and mode of operation is understood.

20 In the accompanying drawing Figure 1 is a diagrammatic illustration of certain parts of a player mechanism including my invention. Fig. 2 is a relatively enlarged section detail view.

25 The purpose of the present invention is to provide means controllable by perforations in a note sheet for varying, either momentarily or for a prolonged period, the effective tension within the action, whereby the action will operate on the sounding devices 30 with different degrees of vigor, depending upon the tension prevailing therein.

1 represents conventionally the action of a pneumatic player mechanism.

2 represents the exhauster.

35 3 represents what I may term a choker-box arranged in the air circuit leading from the action to the exhauster. In this particular instance 4 is the circuit pipe which leads from the action 1 to the choker-box 3, 40 while 5 is the circuit pipe leading from the choker-box 3 to the exhauster 2.

45 6 is a valve arranged in a passage within the choker-box and which is designed to be automatically operated in the manner hereinafter described. 7 is another valve which may be manually controlled for the purpose of adjustment or regulation, such a valve being by preference used, although not essential to the broad invention herein described.

50 8 is a pneumatic, the backboard of which is suitably connected, as by a rod 9, with the valve 6. When the pneumatic 8 is distended, the choker valve 6 is closed. When this pneumatic 8 is collapsed, the valve 6 is 55 moved to open the passage controlled there-

by, so that the action 1 will be put in direct communication with the exhauster 2. When the valve 6 is closed, it should be understood that the exhauster 2 is working on the action 1 through the air duct 10 having the 60 usual regulator 11, which maintains a regulated low degree in the action. This tension may be momentarily, or for such a period as desired, increased by the opening of the valve 6. The pneumatic 8 is connected with 65 the exhauster 2 through the passages 12, 13 and 14, the said passage being controlled by a suitable valve 15 operated by the usual pouch pneumatic 16, which is controlled from the tracker-board, as hereinafter explained.

70 The pneumatic 8 is flushed by being open to atmosphere when the valve 15 stands in the position shown in Fig. 1.

75 17 is a pivoted latch which normally stands in the "off" position shown in solid lines Fig. 1.

18 is a spring which constitutes one simple means for holding it in said "off" position.

19 is a pneumatic for swinging the latch 80 17 to the position indicated in dotted lines, in which position it is arranged to catch and hold the backboard of the bellows 8, the said backboard being provided with a suitable latch-engaging shoulder 20. The pneumatic 19 is connected by a duct 21 with the duct 14 leading to the exhauster 2.

85 22 is a valve housing containing such a valve as 15, previously described, by which said pneumatic 19 may be put in communication with the exhauster or with atmosphere. The valve within the housing 22 is also operated by a pouch pneumatic such as 16, the latter being connected by a duct 23 to a valved outlet leading in one direction to 90 the atmosphere, and in the other direction to a chamber 24 within a housing 25.

95 26 is a valve which opens and closes the duct 23 to atmosphere, while 27 is a valve which is capable of opening and closing the 100 duct 23 to the chamber 24. These two valves 26 and 27 may be suitably connected, as shown in Fig. 1, so that when one is closed the other is open. These two valves 26 and 27 operate independently and are operated by 105 means hereinafter described, which comprises a lift bar 28. The chamber 24 is connected by a pipe 29 with the pipe 14 leading to the exhauster 2, so that a vacuum will be normally maintained therein.

30 is a tracker-board having the usual note perforations 31. The tracker-board at some convenient point, preferably at the end, is provided with one or more groups of expression openings, one group being indicated at A—A'—A''.

32 represents a note sheet arranged to traverse the tracker-board 30 and cover the aforesaid tracker openings. This note sheet 10 may be assumed to move in the direction of the arrow.

33—33^a—34—35—36—37 represent expression perforations in the note sheet for uncovering the aforesaid expression openings 15 A—A'—A'' at certain predetermined times according to the position of said perforations lengthwise of the sheet. The expression opening A is connected by a duct 38 with the pouch pneumatic 16 for valve 15. 20 The expression opening A' is connected by a duct 39 with a pouch pneumatic 40, which is arranged to lift one end of the valve operator 28 within the housing 25. The expression opening A'' is connected by a duct 25 41 with a pouch pneumatic 42 within the housing 25 for lifting the other end of the valve operator 28.

The operation of the apparatus thus far described is as follows: Assuming the expression perforation 33 is approaching the tracker-board—this perforation when it reaches the expression opening A will allow air to enter the pouch pneumatic 16, shifting the valve 15 so as to shut off the entrance 30 of atmosphere into the pneumatic 8 and put the latter in direct communication with the exhauster 2, whereupon said pneumatic 8 collapses and opens the valve 6, thereby putting the action 1 in direct communication 35 with the exhauster 2, and since the tension of air therein is normally greater than the tension of air in the action 1, by reason of the regulator 11, it follows that so long as the valve 6 is open, a higher tension will 40 obtain in the action 1, determined by the adjustment of valve 7. As the sheet continues to move ahead, the perforation 33 will uncover the opening A', which will result in the flushing of the pouch pneumatic 40 and 45 the lifting of one end of the valve operator 28. When the note sheet moves still farther ahead, the perforation 33 will uncover the opening A'' and will flush the pouch pneumatic 42, lifting the other end of the valve operator 28, which is so adjusted that when 50 both ends are lifted it will reverse the position of valves 26—27, opening the duct 23 to atmosphere and closing it to the vacuum within the chamber 24. This will flush the 55 pouch within the primary valve casing 22 and open the valve therein so as to put the pneumatic 19 in direct communication with the exhauster 2, whereby the latter will be collapsed, thus swinging the hook 17 to the 60 dotted position to there engage the locking 65

shoulder 20 on the backboard of the pneumatic 8.

It will be observed that the perforation 33 referred to is of sufficient length to bridge the three expression openings A—A'—A'', 70 which comprise one group. As soon as the rear end of this long perforation 33 passes the opening A, the valve 15 will be reversed and the spring of the pneumatic 8 will tend to expand the same. On the first slight expanding movement, the shoulder 20 is caught by the hook 17 and held so that the pneumatic 8 will continue to be held in a collapsed state with the valve 6 open until released, and as a result the higher tension of 75 the exhauster will continue to prevail in the action 1. When, however, it is desired to close the valve 6, an expression perforation 33^a is caused to traverse the tracker and the opening A. The moment this occurs, 80 the pouch pneumatic 16 will again be extended and the valve 15 reversed from the position shown, and the interior of the pneumatic 8 will again be put in communication with the exhauster 2, whereupon 85 the pneumatic 8 will be drawn down slightly below the latch holding position and sufficient to release the hook 17, which is drawn back by the spring 18 to stand in the disengaging position. The moment the expression 90 perforation 33^a passes the opening A, the valve 15 will return to the position shown in Fig. 1, whereupon the pneumatic 8 will be flushed and will be distended to the position shown in Fig. 1, closing the 95 valve 6. The passage of the perforation 33^a over the openings A' and A'' will have no effect on the pneumatic 19, because the 100 said perforation 33^a is not long enough to bridge the two expression openings A'—A'' 105 in the tracker-board, and hence the valve operator 28 will not be lifted at both ends at one time.

From the foregoing it will be seen that by this simple means an expression controlling 110 pneumatic such as 8 may be moved into operative valve opening position and restored again to the valve closing position by means of two perforations in the note sheet, which perforations may be widely spaced. 115 Were it not for this, or an equivalent arrangement of parts, it would be necessary to provide one practically continuous or long perforation in the edge of the music sheet extending, for example, from the beginning 120 of the perforation 33 to the end of the perforation 33^a, to maintain the pneumatic 8 collapsed for the length of time desired. The provision of a very long perforation 125 near the edge of a music sheet tends to materially weaken the note sheet, and it will therefore be seen to be of great advantage to provide a means whereby the length of the perforations in the music sheet may be abbreviated. In other words, by my im- 130

proved arrangement, the perforation 33 sets the pneumatic 8 in the valve opening position, and the perforation 33^a releases it. It should be understood, of course, that the 5 perforation 33^a is the first perforation which succeeds the perforation 33. I may therefore characterize these perforations respectively as the setting perforation and releasing perforation. Each of the perforations 10 34 to 37 represent merely expression perforations designed to momentarily open the valve 6 for the purpose of securing the accenting of particular notes by momentarily increasing the tension in the action 1, these 15 perforations 34 to 37 being appropriately positioned upon the note sheet 32 with relation to those particular note perforations which control the selection of the solo notes. When any one of these expression perforations 20 34 to 37 crosses the tracker, it will uncover the opening A, which will result in the shifting of the valve 15 and the momentary collapsing of the pneumatic 8 and opening of valve 6. As this particular expression perforation traverses the openings 25 A'-A'', it will have no more effect thereon than the passage thereover of the perforation 33^a previously described.

I have described my invention as associated with only one group of expression openings in the tracker, the same being illustrated by the reference characters A-A'-A'', but it will be plainly seen by reference to the drawing that the number of groups 30 35 of expression openings may be multiplied, there being in this particular instance four groups. Each group of these openings should have associated with it an arrangement of pneumatics and valves such as described in connection with the group A-A'-A''. The purpose of providing a plurality of groups of these expression perforations is to permit of a grading of the tension within the action 1 above the low 40 45 regulated tension. For example, when one group of expression openings in the tracker is employed and one valve 6 opened, the tension within the action 1 is slightly greater than the low regulated tension. If two groups were employed, the tension would be 50 still greater, and so on.

Since there is a choker-box 3 with its valves as described for each group of openings, and since it is preferred to provide a 55 manually adjustable valve 7 in each of said boxes, it is apparent that these valves 7 in the separate choker-boxes may be set so as to give different area of opening, so that by the use of a comparatively few groups of 60 tracker expression openings a large number of tension changes may be secured by combining properly the various groups.

From the foregoing it will be seen that two substantial advantages are obtained. 65 First, by this improvement the note sheet

is relieved in a large measure of unnecessary perforation, and, second, it avoids unnecessarily widening the note sheet, since the marginal perforation such as 33, which opens the valve 6, is arranged on the same 70 line with the perforation 33^a, which closes the valve 6, and is also arranged on the same line with the perforations 34 to 37, which momentarily open the valve 6 for emphasizing certain notes, whereas were it 75 not for this arrangement the said perforations would have to be arranged on different lines so as to traverse different parts of the tracker-board, thereby requiring a longer tracker-board and a wider note sheet. By 80 this improvement this extra widening of the note sheet and lengthening of the tracker-board is avoided, and the note sheet, at or near its edges, where it is subjected to the severest use, is maintained with a maximum 85 degree of strength, because no perforation therein need be longer than that required to bridge one group of tracker openings, which in actual practice need not be separated but very slightly, for example, 90 less than half an inch.

What I claim is:

1. In a player piano having a tracker-board, a pneumatic action, an exhauster, a regulated low tension air circuit leading 95 from the former to the latter, means for abruptly increasing the tension in the action above the regulated tension, controllable from the tracker-board, a group of expression openings arranged in said tracker, the 100 openings of said group being arranged in the line of travel of the note sheet across said tracker in combination with a note sheet having complementary expression perforations arranged in line, one of said 105 perforations being sufficiently long to bridge at least two of said expression openings.

2. In a player piano having a tracker-board, a pneumatic action, an exhauster, a regulated low tension air circuit leading 110 from the former to the latter, means for abruptly increasing the tension in the action above the regulated tension, controllable from the tracker-board, a group of expression openings arranged in said tracker, the 115 openings of said group being arranged in the line of travel of the note sheet across said tracker, said group of openings comprising one opening for abruptly increasing the tension in said action, and means for 120 locking the tension-controlling means in position to prolong the increased tension with at least two openings in the tracker to control said means.

3. In a player piano, a tracker-board having a group of expression controlling openings arranged substantially in the line of travel of the note sheet and arranged to be uncovered by substantially one line of note sheet perforations for controlling the opera- 125 130

tion of said pneumatic instrument, in combination with a note sheet having a series of perforations arranged substantially in line and arranged to traverse said group of 5 tracker openings, one of said note sheet perforations being of sufficient length to bridge all of one group of tracker openings, a relatively shorter complementary note sheet perforation of a size incapable of 10 bridging all of the openings of a group and arranged in the rear of the longer perforation, and another perforation of a size sufficient to open only one of the tracker openings of said group and arranged to operate 15 independently of the first two described perforations and also located in the rear of the second mentioned note sheet perforation.

4. In a player piano, an action, an ex-
hauster, a regulated circuit leading from 20 the former to the latter for maintaining relatively low tension, means for abruptly increasing the relative tension in the action, including suitable normally closed choker mechanism and also a pneumatic for oper-
ating said choker mechanism, a tracker-board, 25 means controllable from the tracker-board for putting said pneumatic in communication with the atmosphere or with the ex-
hauster at will to cause said pneumatic to 30 become distended or contracted, a latch mechanism for holding said pneumatic contracted, a latch operating pneumatic, and means for putting said latch operating pneu-
matic in communication with either the ex- 35 hauster or atmosphere to operate the same, said means being controllable from said tracker-board, said means including a valve with a valve-operating device controllable by two pneumatics, the latter being respec-
tively connected with two openings in the 40 tracker-board in addition to the opening by which the choker pneumatic is controlled,

all of said openings in said tracker being ar-
ranged in substantial alinement in the direc- 45 tion of travel of the note sheet to comprise one group.

5. In a player piano of the pneumatic type, a pneumatic action, an exhauster connected therewith, means for effecting a normal regulated low tension in the action rel- 50 atively to the tension in the exhauster, means for increasing the tension in the action including a normally closed choker with a pneumatic for opening and closing said choker, said pneumatic also being in com- 55 munication with the said exhauster, a nor-
mally closed valve in the line of said com-
munication, a primary pneumatic for con-
trolling said valve, said primary pneumatic
being controlled from the tracker-board and 60 including a duct leading from said primary
pneumatic to an opening in the tracker-
board, two additional openings in the
tracker-board directly behind the first- 65 mentioned opening relatively to the direc-
tion of travel of a note sheet, with means in
communication with the last mentioned two
openings, and including a latch for locking
the choker pneumatic open in the choker 70 opening position when all of said openings
are uncovered at one time, and means for
releasing said latch and freeing said choker
pneumatic when the first mentioned opening
is next uncovered, in combination with 75 a note sheet having the alined perforations
for coacting with said openings, one of said
perforations being long enough to open all
of said tracker openings at one time, and
other perforations long enough to open only
one of said tracker openings at a time. 80
